UNITED STATES PATENT OFFICE.

WILLIAM E. SPARKS, OF NEW HAVEN, CONNECTICUT, ASSIGNOR TO THE SARGENT & COMPANY, OF SAME PLACE.

LOCK.

SPECIFICATION forming part of Letters Patent No. 623,264, dated April 18, 1899.

Application filed May 2, 1898. Serial No. 679,433. (No model.)

To all whom it may concern:

Be it known that I, WILLIAM E. SPARKS, a citizen of the United States, and a resident of the city and county of New Haven, in the State 5 of Connecticut, have invented certain new and useful Improvements in Locks, of which the following is a full, clear, and exact description when taken in connection with the accompanying drawings, which form a part 10 thereof, and in which—

Figure 1 represents a front elevation of a lock embodying my invention, the cap-plate being removed; Figs. 2 and 3, similar views with some of the parts in different positions; 15 Fig. 4, a detail reverse view of the guard-lever, and Fig. 5 a detail view of the guard-bolt.

In all figures similar letters of reference represent like parts.

This invention relates to locks, and has for 20 its object the construction of a novel form of lock the increased security of which is obtained by the peculiar means set forth and claimed hereinafter.

In the drawings the parts designated by 25 the letter A represent the usual case of the lock, and a the face through which the bolt B is adapted to extend.

C represents the hub, through the rectangular slot c of which the knob-spindle (not 30 shown) may extend. The hub is shown herein as a single hub and is provided with two oppositely-disposed arms c' for engagement with shoulders or lugs d on a sliding yoke-plate D, so that upon turning the hub in either direc-

35 tion the yoke-plate is engaged and retracted. The yoke-plate D is guided in its movements by lugs or flanges d' on the interior of the lock-case and is provided with a vertical flange d'' for engagement with the T-shaped 40 heel b of the bolt B. Pivoted on a stud d''' on the yoke-plate is a lever E, which bears with its free end e on the rear of the heel b of the bolt B. A spring F, secured to a post f on the casing, is also attached by a hook e' or 45 other means to the lever E and tends to constantly hold the free end of the lever E against the bolt B to extend it.

The turning of the hub C to the right or left forces the yoke-plate D longitudinally 50 inward, and the yoke-plate D by means of the

engagement of its flange d'' with the bolt B retracts or draws the latter also inward. The lever E, on the other hand, through the tension of spring F, tends to force the bolt outward upon the release of the yoke-plate D 55 from the pressure of the arms c' of the hub C.

The rotary cylinder of a pin-tumbler lock is shown at G with its bit g, which is adapted to engage with and operate the actuating-lever H, pivoted to a post h in the casing. 60 One end k of an auxiliary lever K, pivoted to the post k', is adapted to be engaged by an arm h' of the actuating-lever H when the latter is swung on its pivot by the bit of the cylinder G. The lower end k'' of the auxiliary 65 lever K engages with the T-shaped heel b of the main bolt B to retract the same. A flat spring J, secured to the actuating-lever H, bears against the upper end k of the auxiliary lever and tends to restore the actuating-lever 70 H to its normal position. (Shown in Figs. 1 and 2.)

To retain the bolt in its locked position when engaged with the keeper of the door and prevent its retraction except by the use 75 of the knob or key, a secondary or guard bolt L is provided. This guard-bolt is not provided with any mortise or socket in the keeper of the door, so that when the door is closed and the main bolt B is extended into its mortise or socket of the keeper the guard-bolt L is retracted, as shown in Fig. 2, and when so retracted releases mechanism to lock the main bolt in its extended position.

The guard-bolt L has a depending arm l 85 and a stud l'. To the stud l' and a post l'' in the casing a spring M is secured, normally tending to keep the guard-bolt in its extended position. (Shown in Fig. 1.) A bell-crank lever or guard-lever N is provided with the arms 90 n, n', and n'', and a spring O is secured to it and a post o in the casing, tending to hold it in the position shown in Fig. 2. When in such position, Fig. 2, the arm n of the lever is dropped downward behind the heel of the 95 main bolt B, and thus prevents the main bolt from being retracted. When, on the other hand, the guard-bolt L is extended by the action of the spring M, the depending arm l comes in contact with a seat n''' on the guard- 100

lever N and swings the guard-lever on its pivot against the tension of the spring O until the arm n is raised from engagement with the heel b of the main bolt, allowing the bolt to be retracted, if desired, Fig. 1. This position of the guard-bolt, guard-lever, and main bolt shown in Fig. 1 is assumed when the door is in its opened position and the bolts clear of the keeper. The arm n^2 of the guard-lever N limits its movement under pressure of the guard-bolt L by striking against an abutment a² in the casing.

As the latch l⁸ of the guard-bolt is shorter than the latch b' of the main bolt, as the door is closed the keeper first retracts the main bolt B sufficiently for the heel b to clear the arm n of the guard-lever N, so that the main bolt may be fully retracted prior to shooting into its socket or mortise of the keeper. As the guard-bolt is retracted the guard-lever is released, and as the main bolt is shot into its mortise the guard-lever N is swung on its pivot by the spring O and the arm n drops into engagement in the rear of the heel of the main bolt to prevent any movement thereof.

To retract the main bolt (by means of the knob or key) when in its locked position in engagement with its keeper, as shown in Fig. 2, the guard-lever must first be swung out of engagement with the main bolt independently of the guard-bolt, which is in its retracted position. A toggle-link P is pivoted at one end to the under side of the arm n of the guard-lever N (see Fig. 4) and is adapted to bear with its other end in a socket d⁸ in the edge of the sliding yoke-plate D. Upon the retraction of the yoke-plate D and, by means of the flange d', the main bolt B the end of the link P in the socket d⁸ is forced backward and the arm n of the guard-lever N is swung upward sufficiently to clear the arm from engagement with the heel b of the main bolt B. The lifting effect of the link P takes place just prior to the retraction of the main bolt, so that the movement of the guard-lever is very slight, Fig. 3. The link P also acts to limit the reverse movement of the guard-lever N, so that the lever swings only so far as necessary to engage with the heel of the main bolt B, as shown in Fig. 2.

When the guard-bolt L is retracted and the guard-lever N in engagement with the main bolt, the arm n' of the lever N is swung forward to the position shown in Fig. 2, so that upon the movement of the actuating-lever H by the bit g of the cylinder G the free end of the lever H will come in contact therewith and swing it rearward. By such rearward movement of the arm n' by the actuating-lever H the guard-lever N is swung on its pivot and the arm n raised from engagement with the main bolt B. As the radius of the arc described about the pivot h by the free end of lever H is greater than that of the arc of the arm h', which operates the auxiliary lever K, the free end of the lever H travels faster, and

by the single movement of the actuating-lever H the guard-lever is swung away from the main bolt faster than the main bolt is retracted by the auxiliary lever K.

Having now described my invention, what I claim, and desire to secure by Letters Patent, is—

1. In a lock, the combination with the main bolt; of a cylinder-lock; a guard-lever pivoted to swing to engage the main bolt to lock it in its extended position; a spring normally tending to swing said guard-lever into such engagement; a pivoted actuating-lever operated by the bit of said cylinder-lock and when so operated adapted to swing said guard-lever from engagement with said bolt, and retract said bolt, substantially as described.

2. In a lock, the combination with the casing of the lock; of the main bolt; a cylinder-lock; a guard-lever pivoted to swing so that an arm thereof may engage the main bolt to lock it in its protracted position; a spring normally tending to swing said guard-lever into such engagement; an actuating-lever pivoted to the casing and swung on its pivot by the bit of said cylinder-lock to engage another arm of said guard-lever to swing it from engagement with said bolt, substantially as described.

3. In a lock, the combination with the main bolt; of a yoke-plate capable of a limited sliding movement operated by the hub, and having an engagement with the main bolt to retract the same; a guard-lever pivoted to swing so that an arm thereof may engage the heel of the main bolt to lock it in its extended position; a spring normally tending to swing said guard-lever into such engagement; a toggle-link between said guard-lever and yoke-plate, being pivoted to one member to swing the guard-lever from engagement with said main bolt upon the longitudinal movement of said yoke-plate, substantially as described.

4. In a lock, the combination with the main bolt; of a cylinder-lock; a pivoted actuating-lever operated by the bit of said cylinder; an auxiliary lever operated by said actuating-lever and adapted to engage with and retract the main bolt; a guard-lever pivoted to swing so that an arm thereof may engage the heel of said main bolt to lock it in its extended position; a spring normally tending to swing said guard-lever into such engagement, said guard-lever being also engaged by said actuating-lever to be swung thereby out of engagement with said main bolt upon the operation of said key-bolt, substantially as described.

5. In a lock, the combination with the main bolt; of a yoke-plate capable of a limited longitudinal movement operated by the hub and having an engagement with said main bolt to retract the same; a pivoted actuating-lever operated by a cylinder-lock; an auxiliary lever operated by said actuating-lever and adapted to retract said main bolt; a guard-

lever pivoted to swing so that an arm thereof may engage with said main bolt and lock it in its extended position; a spring normally tending to swing said guard-lever into such engagement; and a guard-bolt which when in its extended position engages with and swings said guard-lever from such engagement; and mechanisms connected with said actuating-lever and yoke-plate to disengage said guard-

lever from said main bolt, substantially as described.

In witness whereof I have hereunto set my hand this 27th day of April, A. D. 1898.

WILLIAM E. SPARKS.
